(57) **CLAIM**

The ornamental design for a triangular trampoline, as shown and described.

DESCRIPTION

FIG. 1 is a perspective view.

FIG. 2 is a front view.

FIG. 3 is a rear view.

FIG. 4 is a left side view.

FIG. 5 is a right side view.

FIG. 6 is a top view.

FIG. 7 is a bottom view.

FIG. 8 is a perspective view of the triangular trampoline with the handle in a folded configuration; and,

FIG. 9 is a top view of the triangular trampoline with the handle in a folded configuration.
